UNITED STATES PATENT OFFICE.

RALPH R. LEFFLER, OF CHICAGO, ILLINOIS.

REINFORCED-CONCRETE SHIP AND METHOD OF CONSTRUCTING SAME.

1,305,379.

Specification of Letters Patent. Patented June 3, 1919.

Application filed May 31, 1918. Serial No. 237,534.

To all whom it may concern:

Be it known that I, RALPH R. LEFFLER, a citizen of the United States, residing at Chicago, in the county of Cook and State of Illinois, have invented certain new and useful Improvements in Reinforced-Concrete Ships and Methods of Constructing Same, of which the following is a specification.

This invention relates to reinforced concrete construction and more particularly to such construction as applied in the building of ships.

During the present great demand for ships many concrete ships are being built and many more will be planned for the future. If these concrete ships are to be a commercial success after the war it is almost essential that their hull weight shall not substantially exceed that of steel ships; and to 20 make possible this result and at the same time secure adequate strength together with economy in manufacture, neatness and simplicity of design and general improvement in reinforced concrete construction is the 25 aim of the present invention.

Among the objects of my invention is to so improve reinforced concrete construction that long floors or the like can be constructed without the use of massive cross beams or other unduly heavy parts whereby to obtain the maximum of strength with the minimum of weight; further to eliminate in ship construction the necessity of spaced transverse frames; further to make possible a longitudinally and transversely continuous double concrete shell requiring no planking or the like; further the construction of the bottom of a ship after the manner of a double diagonal concrete Pratt truss; further to extend the beams or the verticals of the truss almost the length of the ship thus carrying any local inequality of loading a greater distance longitudinally than in the old type employing transverse framing; further to form the diagonals of the Pratt truss of metal rods or bolts; further to also form the sides of the hull of Pratt truss construction extending either the full height or any fractional distance desired; further to provide vertical beams to extend over that portion of the sides which may not be covered by the Pratt truss construction; further to provide steel plates on the inside of the concrete vertical beams to carry longitudi-

dinal shear and serve as an inner wall or shell; further to provide angle bars to transmit the stress from the metal diagonals to the connecting truss members and at same time serve as longitudinal reinforcement of the ship; further to notch the angle bars to permit the reinforcing bars of the chords to drop into the legs of the angle bars; further to notch the top portion of the truss verticals or intercostals to effect a more efficient connecting of the adjacent concrete fillet and also of the intercostal with the upper and lower shell portions or floor; further to firmly secure the diagonals of the Pratt truss construction to the respective arms of the angle bars; and such further objects, advantages and capabilities as will later more fully appear.

My invention further resides in the combination, construction and arrangement of parts illustrated in the accompanying drawings, and while I have shown therein a preferred embodiment I desire the same to be considered as illustrative only and not as limiting the scope of my invention.

Referring to the drawings:

Figure 1 is a transverse vertical section illustrating my invention as embodied in a ship, one half being omitted for the reason that the two halves are symmetrical.

Fig. 2 is a fragmentary plan view of a portion of the floor showing the arrangement of the reinforcing and angle bars.

Fig. 3 is a fragmentary vertical section through the upper portion of the floor.

Fig. 4 is a plan view of a portion of one of the truss verticals or intercostals.

Fig. 5 is a section on the line 5 of Fig. 3.

Fig. 6 is a section on the line 6 of Fig. 3, but omitting all parts except the truss verticals and the angle bars for the sake of clearness in showing this construction.

Fig. 7 is a fragmentary longitudinal transverse section on the line 7 of Fig. 1.

Fig. 8 is a side elevation of Fig. 6.

Fig. 9 is a vertical transverse section through one of the truss verticals or intercostals and showing the angle bars in position at the top and bottom edges thereof.

In the drawings I have illustrated my invention as embodied in the construction of ships, and referring to Fig. 1, it will be seen that such ship comprises the bottom 1, sides 2, braces 3, vertical side beams 4, main deck

5 and bilge block 6. As will be seen, the bottom is of double diagonal concrete Pratt truss construction, which truss construction may also extend a suitable distance up the 5 sides of the hull, which distance I have illustrated in the drawing as reaching to the neutral axis of the ship; however, it is obvious that if desired this Pratt truss construction may be extended up the side of the hull entirely to the main deck, or a fractional portion 10 of such distance if desired.

In Fig. 1 the construction of the sides of the hull lying between the upper end of the truss construction and the main deck comprises 15 the single outer shell 7, (which of course will be suitably reinforced), and the vertical beams 4 on the inner edges of which are secured the steel plates 8 suitably riveted together and anchored at their upper and 20 lower edges in the concrete as shown.

Referring to Fig. 7, it will be seen that I have provided the vertically extending angle plates 9, which are suitably secured to the steel plates 8, and through the other leg 25 of which extends the bolts 10' into the concrete of the ribs 4. Also bolts or projections 111 are provided extending from the plates 8 into the concrete of the rib 4. This construction will secure the plates 8 in a firm 30 manner to the ribs 4. These plates 8 serve the double purpose of carrying the longitudinal shear and also serving as an inner wall or shell.

By providing the braces 3 and I beams 28 35 the length of the bottom truss will be divided up into substantially three equal portions, and instead of having, say for example, in a ship of 45 foot beam, a truss spanning 45 feet there will be three trusses 40 each spanning approximately 15 feet, thus shortening the spans and decreasing the magnitude of the stresses caused. The cross braces will be suitably secured by means of I beams 10 to the ribs 4, and to the sides 45 of the hull.

Turning now to the details of the double diagonal concrete Pratt truss construction, and referring to Figs. 2 to 9, it will be seen that I have provided the truss verticals or 50 intercostals 11, which are precast; that is molded and hardened prior to the construction of the ship bottom and sides. These intercostals or truss verticals are provided at suitable distances with the outwardly extending ribs or wings 12 to give the necessary 55 rigidity and strength. As will be seen in Figs. 6 and 9, the longitudinal edges of the intercostals are formed with V-shaped grooves, in which V-shaped grooves are inserted 60 the angle bars 13, which bars, while shown as forming an angle of 90°, may be of any other desired angularity, the essential feature being that the respective arms of these bars occupy a position at substantially 65 right angles to the diagonal rods 14, see

Fig. 5. The intercostals 11 are notched or recessed at their upper and lower edges as indicated at 15, the ends of which notches or recesses may, if desired, be of dove tail formation, as indicated at 16 whereby to securely unite the concrete of the fillet thereto. Near the ends of the notches 15 and embedded in the intercostals 11 are the staples 17, which extend into the recesses 15 a suitable distance to receive and permit to extend therethrough the rods 18, which as shown in Fig. 5 extend from the upper portion 19 of the bottom down through the fillet 20, and up on the other side of the intercostals again entering the upper portion 80 19, thus firmly reinforcing and securing together the concrete of the upper portion 19, the fillets 20, and the intercostals.

Extending longitudinally through the fillets 20 are the reinforcing bars 21, which 85 may be square or of any other suitable cross section. Resting upon the upper surfaces of these bars 21 are the transverse reinforcing bars 22, which bars will be noted are located below the neutral axis of the upper portion 90 19 of the truss construction. The angle bars 13, as will be seen in Fig. 8, are provided with the notches 23, the function of which is to permit the transverse rods 22 to be seated therein, thus accommodating these 95 bars to the desired height, and rendering possible the securing of a minimum of thickness for this shell construction. As seen in Fig. 6, the slots 23 are formed by providing suitable slits in the sides of the metal and 100 bending the portion 23' outwardly. Also extending transversely of the upper portion 19 of the floor are the smaller reinforcing rods 24, which may during the process of placing the concrete be held at the appropriate 105 height by placing other rods between these rods and the upper surface of the rods 22, or any other appropriate manner.

Referring to Fig. 5, it will be seen that the diagonal rods 14, extending through the angle bars 13 are provided with nuts 25, which when assembling the parts may be suitably tightened to secure the diagonals 14 to the angle bars 13. It will also be noted that the ends of the diagonals 14 at a little distance 115 beyond where they pass through the angle bars 13 are bent downwardly, as indicated at 26 to lie in a plane of the floor 19, thus providing further reinforcement in this region. It is to be understood that the details of 120 construction at the juncture of the bottoms of the intercostals 11 and the outer shell 27 are the same as those described above for the upper shell 19; the diagonals 14 passing from one edge of one of the upper angle 125 bars 13 to a diagonally opposite lower bar 13, as clearly seen in Fig. 1. The lower end of the brace 3 is suitably secured to the I beam 28 incorporated in the bottom of the vessel.

The Pratt truss construction will be extended to the sides of the bottom, at which point they will merge into the bilge block 6, in which bilge block is suitably located appropriate reinforcing means together with the lower edge of the steel plates 8, as clearly shown in Fig. 1. As stated above, the double diagonal Pratt truss construction will be continued upwardly from the upper portion of the bilge block to the desired height. The method of construction of my improved structure is as follows:

The truss verticals or intercostals 11 are first formed and hardened. All bars and reinforcing elements are then placed in an appropriate manner in the exterior or outer shell of the bottom and also in both the exterior and interior shells of the sides. The preformed truss verticals or intercostals are next placed in position, and the metal diagonal rods or bolts 14 are then placed and the nuts 25 suitably tightened to give the necessary rigidity. The exterior bottom shell is then poured, which pouring is continued until the bilge blocks at each side of the bottom are reached, which bilge block is then formed and the pouring continued until both the exterior and interior shells of the sides as far up as the Pratt truss construction is extended are completed. It is here pointed out that in the formation of the Pratt truss construction in the sides that suitable metal of the hy-rib type will be placed to form the inner sides of the exterior and interior shells, it of course being understood that suitable molds will be provided for the exterior of the outer shell of the side, while the steel plates 8 will form the mold for that side of the inner shell toward the inside of the hull. The sides of the hull being completed, the reinforcing bars are then placed in the interior shell portion 19 of the bottom, hy-rib metal having previously been inserted and secured in place to form the underneath side of this upper shell 19, which hy-rib metal will be of appropriate shape to form the fillets 20, which fillets as pointed out above extend through and are anchored in the recesses 15. While I have mentioned hy-rib, it is of course understood that any other suitable form of metal lath may be used in this connection. The upper shell 19 of the bottom is then poured and completed.

By thus making use of the double diagonal Pratt truss construction in forming the bottoms and sides or portions of the sides of concrete ships, it will be seen that I have greatly reduced the weight of such vessels while at the same time preserving the necessary strength. By using double diagonals in the Pratt truss construction, there is provided at all times a rod to carry the tension which may be set up in either of these diagonals, due to a reversal of stresses in the

ship caused by the different positions at which the vessel rides on the waves. If desired an additional nut similar to the nut 25 may be provided on the opposite side of the angle bar 13 and the diagonals 14 thus enabled to carry a certain amount of compression, should the same be necessary. This construction results in the elimination of the heretofore used and massive transverse framing, and thus not only reduces the weight of the vessel to a considerable extent, but as a result of the double diagonal Pratt truss construction the stresses will be much more evenly divided over the ship and successfully taken care of in a manner quite similar to that accompanying the use of mushroom construction in the erection of floors and ceilings in reinforced concrete buildings. While the main function of the angle bars 13 is to carry the longitudinal stresses caused by the movement of the ship when acting as a beam, or as a truss, it is pointed out that the incidental function of forming anchors for the diagonal rods 14 is considered as nearly, if not fully, as important. These angle irons are arranged in staggered relation with respect to the joints of the truss verticals or intercostals, so as to overlap these joints. The nuts on the diagonal rods 14 are tightened prior to pouring the exterior shell and again prior to pouring the interior shell whereby to insure the necessary rigidity in these parts.

If some designer should prefer not to use the steel plates 8 this construction could be modified so as to provide a lattice truss as a substitute thereof either in the exterior or interior shell.

In constructing the Pratt truss in the sides of the hull the outstanding leg of the vertically extending angle plates 9 can be notched to support the inner ends of the truss verticals or intercostals in the sides, and may have holes punched therein through which the round rods referred to above can be inserted to further bind the concrete and the angle web. The thickness of the sides of the ship can be increased or decreased as desired without markedly affecting the weight of the hull.

Concrete vessels built after the type of the well known concrete ship "Faith" will weigh from fifteen to twenty-five per cent. more than the hull of a similar steel ship. The weight of the hull constructed, according to the present invention, will weigh approximately the same as a steel hull.

When applying my invention in the construction of stationary buildings it is possible and entirely practicable to span forty feet or more without the necessity of using any intermediate columns. A building approximately forty feet in width and of indefinite length could be constructed without

the use of any intermediate columns whatever, thus permitting the maximum of daylight to enter due to the absence of obstructing columns, and in such a construction the 5 entire floor could be considered as a large concrete truss slab. In a wider building having columns the truss slab could be considered the entire portion extending between columns or supports; while in the 10 form of ship illustrated in Fig. 1 the respective truss slabs would be those portions of the floor (including both interior and exterior shells and the intercostals) lying between supports, that is between the respective 15 I-beams 28, and between these I-beams and the bilge blocks; also that portion of the sides above the bilge block. These portions could each be considered alone as a large truss slab.

20 Having now described my invention I claim:

1. In a reinforced concrete ship, a hull having sides and a bottom, the bottom comprising spaced apart reinforced concrete shells, 25 concrete intercostals connecting said shells, and double diagonals of metal rods connecting the diagonally opposite edges of said intercostals whereby said bottom will be of double diagonal Pratt truss construction to 30 accommodate all possible stresses set up therein.

2. In a reinforced concrete ship, a hull having sides and a bottom, the bottom comprising spaced apart reinforced concrete shells, 35 concrete intercostals connecting said shells, and double diagonals of metal rods connecting the diagonally opposite edges of said intercostals whereby said bottom will be of double diagonal Pratt truss construction to 40 accommodate all possible stresses set up therein, said double diagonal Pratt truss construction also extending partially up the sides.

3. In a reinforced concrete ship, a hull 45 comprising a side having a portion of its height of double shell formation, concrete intercostals connecting said shells, double diagonals of metal rods connecting the diagonally opposite edges of said intercostals 50 whereby this portion of the side will be of double diagonal Pratt truss construction, said side for the remainder of its height being of single concrete shell construction with vertical beams.

55 4. In a reinforced concrete ship, a hull comprising a bottom of hollow double shell reinforced concrete construction having concrete verticals, and double diagonals of metal rods connecting the diagonally opposite edges of said verticals.

5. In a reinforced concrete ship a double shell of double diagonal Pratt concrete truss construction and comprising truss verticals each having an angle bar on its upper and 65 lower edges, metal rod diagonals extending

from the upper edge of the verticals to the lower edge of the adjacent vertical, said diagonals being secured to said angle bars.

6. In a reinforced concrete ship, a hull having a double shell of double diagonal 70 Pratt truss construction comprising truss verticals or intercostals, diagonals of metal rods extending between said verticals, and angle bars to which said diagonals are secured, said angle bars carried by the edges 75 of said verticals and serving as anchors for said diagonals and at the same time as longitudinal reinforcement of the ship.

7. In a reinforced concrete ship, a hull having a double shell bottom of double diagonal 80 Pratt truss construction comprising concrete truss verticals, angle bars along the edges thereof, and diagonal rods connecting said angle bars, the upper and lower edges 85 of said verticals being recessed to accommodate fillets, fillets in the recesses, said fillets being integral with the shell portions and acting therewith to embrace said angle bars.

8. In a reinforced concrete ship, a hull 90 having a double shell of double diagonal Pratt truss construction comprising truss verticals, an angle bar on each of said verticals, diagonal rods rigidly connecting said angle bars, reinforcing rods, and said angle 95 bars each having notches to receive said reinforcing rods.

9. In a reinforced concrete ship, a hull having a double shell of double diagonal truss construction comprising truss verticals, 100 angle bars on the upper and lower edges respectively of said verticals, and rods connecting the diagonally opposite angle bars, said rods passing through and secured to said bars and extending therebeyond for a 105 substantial distance in the plane of the shell member.

10. The construction of reinforced concrete ships having double shells of double diagonal Pratt truss construction which consists in providing preformed intercostals, laying the reinforcement including longitudinal angle bars of the outer shell, placing the intercostals in position on said angle bars, placing angle bars on the upper edge of said 115 intercostals, connecting the alternate upper and lower angle bars by diagonal rods, tightening said rods, pouring the outer shell, placing metal lath to form the lower surface of the interior shell, placing the reinforcement thereon and pouring the interior shell. 120

11. The construction of reinforced concrete ships having double shells of double diagonal Pratt truss construction which consists in arranging the reinforcement of the 125 exterior shell including longitudinal angle bars, placing precast intercostals thereon, placing similar but reversely positioned angle bars along the opposite edge of said intercostal, connecting said intercostals by di- 130

agonal rods, arranging the reinforcing rods of the interior shell, and pouring the concrete of said shells.

12. In double diagonal concrete Pratt truss ship construction, a plurality of intercostals having recesses in their upper and lower edges, angle bars on the upper and lower sides of said intercostals, diagonal

rods connecting the alternate upper and lower angle bars, interior and exterior shells, and fillets connecting said intercostals and said shells, said fillets extending through and on both sides of said recesses.

In witness whereof, I hereunto subscribe my name to this specification.

RALPH R. LEFFLER.
